LIGHT-DIRECTING SHADE

Charles A. Jerabek, Bay Shore, and Robert L. Monahon,
New York, N. Y., assignors to The Phoenix Glass Com-
pany, Monaca, Pa., a corporation of West Virginia

Application May 13, 1954, Serial No. 30,463

Term of patent 7 years

(Cl. D48—16)

FIG. 1.

FIG. 2.

FIG. 3.

To all whom it may concern:

Be it known that we, Charles A. Jerabek and Robert L. Monahon, have invented a new, original, and ornamental Design for a Light-Directing Shade, of which the following is a specification, reference being had to the accompanying drawing, forming a part hereof.

Fig. 1 is a side elevational view of a light-directing shade showing our new design.

Fig. 2 is an end elevational view of the same article, looking at the right of Fig. 1.

Fig. 3 is a view looking upwardly at the article as shown in Fig. 1.

We claim:

The ornamental design for a light-directing shade, as shown.
